PAPER BOTTLE CONSTRUCTION

Frank D. Palmer, Chicago, Ill., assignor to Frank D. Palmer, Inc., a corporation of Illinois

Application February 8, 1946, Serial No. 646,435

9 Claims. (Cl. 93—36.8)

1

This invention relates to an improvement in paper bottle construction and although susceptible of other use, it has particular reference to the construction of paper milk bottles.

Paper milk bottles have already been quite widely adopted in the dairy industry but in the main, they have been adopted only by the larger milk companies who are well able financially to procure the necessary paper bottle making equipment, and who have the facilities for installing and operating such equipment together with sterilizing equipment, usually in the form of paraffining machinery and special filling machinery adapted for the filling of paper bottles. There are many smaller dairies who find it impracticable because of financial considerations to adopt paper bottles for their relatively small distribution of bottled milk.

The present invention has for its object the provision of a paper milk bottle of exceptionally simple form but which is nevertheless adequately leak-proof, of good appearance, and capable of being set up either by the dairy company or by a package forming concern without the addition of special costly package forming equipment.

Other objects and advantages of the invention will be understood by reference to the following specification and accompanying drawing (one sheet) wherein there is illustrated a paper milk bottle embodying a selected form of the invention.

In the drawing,

Fig. 1 is a plan of the blank employed in forming the paper bottle herein shown;

Figs. 2 and 3 are perspectives of the bottom end structure showing successive steps in the closing of said end of the container;

Fig. 4 is a vertical section through the container on the plane represented by the line 4—4 of Fig. 3;

Fig. 5 is, in part, a section on the line 5—5 of Fig. 4, and in part, a side elevation in which there is illustrated a device which may be employed in the operation of closing the bottle.

Each of these figures, 2 to 5 inclusive, represents the container in an inverted position, i. e., with the bottom end up.

The improved paper bottle herein shown is formed from a blank of the character illustrated in Fig. 1. The blank is suitably creased to form body panels 1, 2, 3 and 4 and a gluing flap 5 which, in the process of forming the blank into a carton, is overlapped on the free marginal edge portion of the flap 1 and adhesively or otherwise

2

secured thereto so as to form the blank into a rectangular tube.

One end of the tube is closed by means of short flaps 6 and 7 formed integrally with the wall panels 2 and 4 and flaps 8 and 9 respectively formed integrally with the walls 1 and 3. The flaps 6 and 7 are first folded inwardly, then the flap 9 and thereafter the flap 8. The flap 9 is equipped with cut scoring indicated at 10 and 11 to form removable sections 12 and 13.

The flap 8 is equipped with cut scoring 14 which cooperates with a hinge formed by a crease 15 to form a hinged ear 16 which will overlie the removable portion 12 of the flap 9. The flap 8 is also provided with scoring 17 which is extended into a flap extension 18 where the ends of the score lines are joined by a composite line of severance formed by centrally disposed slitting indicated at 19 and scoring indicated at 20—23. The ends of the score lines 17 in the flap 8 are joined by a crease formed hinge line 21. The ear 22 surrounded by the lines 17—17, 20—23, 19 and 21 will overlie the removable element 13 of the flap 9.

25 The side margins of the flap 9 are adhesively united to the inturned flaps 6 and 7 and the flap 8 is adhesively united to the underlying flap 9 except that the ears 16 and 22 are saved against adhesive attachment of any area of the flap 9 outside of the removable elements 12 and 13. The ear 16 is adhesively attached to the element 12 and the ear 22 is adhesively attached to the element 13.

In the production of a carton embodying this form of end closure, the ear 16 and removable element 13 will initially be displaced as a unit about the hinge line 15 to provide a filling opening indicated at 23 in Fig. 4. The ear 22 and the element 13 will remain in their normal closed condition and the ear 22 will not be displaced from the flap 8 and its extension 18 until in the hands of the consumer, who will be the first one to open the ear 22 and element 13. This end construction may be considered the top end and it is substantially in accordance with the structure shown in my co-pending application Ser. No. 632,251, filed December 1, 1945. The flap extension 18, as best shown in Fig. 4, overlies the adjacent end portion of the wall 3 and is adhesively attached thereto except that no portion of the ear 22 is adhered to the wall 3.

50 The bottom end of the container is closed by means of a pair of flaps 24 and 25 which extend from the wall panels 1 and 3 respectively, and a pair of flaps 26 and 27 which extend from the

wall panels 2 and 4 respectively. The flaps 24 to 27 inclusive, like the flaps 6 to 8 inclusive, are hingedly connected to the respective wall panels by means of creasing in the usual manner.

The flaps 24 and 25 are of such length that they each extend across substantially one-half the corresponding dimension of the end area of the container body and the flaps 26 and 27 are each of substantially full size, that is to say, of such size that they each cover substantially the entire end area of the container body. The flaps 24 and 25 are first folded inwardly, then either the flap 26 or the flap 27 followed by the remaining one of these two.

To insure leak-proofness in the bottom of the container around the corners formed by folding the flaps 24 to 27 inwardly as already explained, a suitable paper strip 28 is provided, said strip extending continuously from the edge 29 of the carton blank to the edge 30 thereof and being arranged to overlap approximately equal portions of the blank on opposite sides of the fold lines which join the flaps 24 to 27 inclusive, to the respective wall panels. It is not essential that the strip 28 extend equally to both sides of the fold lines joining the said flaps to the wall panels and it may be so arranged as to extend farther to one side of said fold lines than to the other. However, the arrangement shown is satisfactory.

The strip 28 is adhesively secured to the wall panels and flaps so that when the said flaps are folded to closure forming position the corresponding portions of the strip 28 are also folded. The initial position is illustrated in Fig. 2 wherein the flaps 24 to 27 inclusive, are shown in an upwardly extending relation to the ends of the respective wall panels from which they extend and the corner sealing strip is shown approaching the fold lines on which the respective flaps are foldable. The first step in closing the container is to fold the flaps 24 and 25 inwardly as shown in Fig. 3. This is, of course, accompanied by corresponding folding of the underlying portions of the strip 28, corner portions thereof being folded over as indicated at 31—31 on the portions carried by the flaps 26 and 27. The flaps 26 and 27 are next folded inwardly, the flap 27 being shown first folded over, the flaps 24 and 25 and the flap 26 over the flap 27, although this order in respect of the flaps 26 and 27 may be reversed. The provision of the strip 28 serves to provide a substantially continuous band in the bottom corner of the paper bottle with consequent reduction of the possibilities of leakage developing in said corners.

By paraffining the bottle either by spraying or by immersion in a bath of molten paraffin, preferably by the latter method, all voids between any parts of the bottom structure will be filled with paraffin so that leakage is more effectively prevented.

Containers such as here described are usually formed about a solid mandrel against which the end closure flaps are pressed while effecting adhesive inter-attachment of the flaps forming the end closure. However, with the described construction it is practicable to close the end closure flaps against compressed air delivered into the container through the filling opening 23 by means of an air nozzle 32 which is connected to a suitable source of compressed air. The flaps 24 and 25 may, of course, be initially folded inwardly without regard to any support therefor but adhesive attachment of the flaps 26 and 27

5 to each other and to the underlying flaps 24 and 25 require some support for the flaps 24 and 25 so that pressure may be exerted on the outermost flap 26 to effect intimate adhesive bonding of these flaps.

10 The sealing strip 28 is not essential in the described construction or in the described method of closing the container end against the support provided by the air cushion in the container. However, by the provision of the sealing strip, leakage of compressed air from within the container is resisted to such an extent that an adequate air cushion can more easily be built up in the container to support, or in effect, to press the flaps 24 and 25 outwardly against the over folded flaps 27 and 26. The flaps 27 and 26 may be manually or mechanically held in the desired folded condition as, for example, by means of a shoe represented at 33, which may be a normally stationary member under which the formed containers are propelled in the process of closing the bottom end of the container. The shoe may be hollow and provided with inlet and outlet openings to permit circulation of a tempering or cooling medium through the shoe for controlling or expediting the setting of the adhesive between the flaps. The sealing strip 28 prevents leakage of compressed air outwardly between the adhesively united flap surfaces and thereby avoids any tendency to produce imperfectly bonded flaps. If desired, suitable means may be provided for sealing the opening 23 around the nozzle 32 to prevent air leakage at that point, but this is not necessary since an adequate supply of pressure air may include enough to compensate for such leakage. Also, it should be understood that it is preferable that only sufficient air pressure to adequately support the inner flaps be employed.

15 30 35 40 Various changes in the described arrangement may be made without departing from the invention as described.

I claim:

1. The method of closing a container comprising a tubular body having flaps at one end adapted to be folded into mutually overlying relation to close such container, which consists in delivering compressed air into the container, folding the flaps successively inwardly into closure forming position against the air cushion within the container, and effecting adhesive inter-attachment of the mutually engaging surfaces of said flaps.

2. The method of closing a container comprising a tubular body having flaps at one end adapted to be folded into mutually overlying relation to close such container, which consists in providing the container with a sealing strip overlying portions of the container body and closure flaps on opposite sides of the fold lines about which the flaps are foldable into closure forming position, delivering compressed air into the container and maintaining such air delivery to compensate for air escaping from the container to thereby maintain an air cushion within the container, folding the flaps successively inwardly into closure forming position against the air cushion within the container, and effecting adhesive inter-attachment of the mutually engaging surfaces of said flaps, said sealing strip serving to prevent the escape of compressed air into the areas of adhesive inter-attachment to thereby insure effective bonding of said flaps together in closure forming position.

3. The method of closing a container comprising

ing a tubular body having flaps at one end adapted to be folded into mutually overlying relation to close such container, which consists in providing the container with a sealing strip overlying portions of the container body and closure flaps on opposite sides of the fold lines about which the flaps are foldable into closure forming position, delivering compressed air into the container, folding the flaps successively inwardly into closure forming position against the air cushion within the container, and effecting adhesive inter-attachment of the mutually engaging surfaces of said flaps, said sealing strip serving to prevent the escape of compressed air into the areas of adhesive inter-attachment to thereby insure effective bonding of said flaps together in closure forming position.

4. The method of closing a container embodying a tubular body having one end closed and provided with a filling opening and its other end provided with adhesive bearing flaps adapted to be folded into mutually overlapping, adhesively interconnected relation in closure forming position on said other end of the body, which consists in delivering compressed air into the body of the container through said filling opening, and then folding said flaps into closure forming position and holding the outermost of said flaps in said position while the air pressure within the container presses said flaps into intimate interengagement.

5. The method of closing a container embodying a tubular body having one end closed and provided with a filling opening and its other end provided with adhesive bearing flaps adapted to be folded into mutually overlapping, adhesively interconnected relation in closure forming position on said other end of the body, which consists in providing the container with a sealing strip on its inside and overlying portions of the closure flaps and tubular body on opposite sides of the fold lines on which said flaps are foldable into closure forming position, delivering compressed air into the body of the container through said filling opening, and then folding said flaps into closure forming position and holding the outermost of said flaps in said position while the air pressure within the container presses said flaps into intimate interengagement, said sealing strip serving to prevent the escape of compressed air into the zones of inter-engagement between said flaps.

6. The method of closing a container embodying a tubular body having one end closed and provided with a filling opening and its other end provided with adhesive bearing flaps adapted to be folded into mutually overlapping, adhesively interconnected relation in closure forming position on said other end of the body, which consists in delivering compressed air into the body of the container through said filling opening, then folding said flaps into closure forming position and holding the outermost of said flaps in said position while the air pressure within the container presses said flaps into intimate interengagement, and coating the container inside and out with water proofing material.

7. The method of closing a container embodying a tubular body having one end closed and provided with a filling opening and its other end provided with adhesive bearing flaps adapted to be folded into mutually overlapping, adhesively interconnected relation in closure forming position on said other end of the body, which consists in providing the container with a sealing strip on its inside and overlying portions of the closure flaps and tubular body on opposite sides of the fold lines on which said flaps are foldable into closure forming position, delivering compressed air into the body of the container through said filling opening, then folding said flaps into closure forming position and holding the outermost of said flaps in said position while the air pressure within the container presses said flaps into intimate interengagement, said sealing strip serving to prevent the escape of compressed air into the zones of inter-engagement between said flaps, and coating the container inside and out with water proofing material.
8. The method of closing a container comprising a tubular body having one end closed and provided with a filling opening and its other end provided with adhesive-bearing flaps adapted to be folded into closure-forming position on said other end of the body, which consists in folding said flaps into closure-forming position, holding the outermost of said flaps in said position, and delivering compressed air into the body of the container through said filling opening so as to cause said compressed air to press said flaps into intimate, adhesively secured interengagement.
9. The method of closing a container comprising a tubular body having one end closed and provided with a filling opening and its other end provided with adhesive-bearing flaps adapted to be folded into closure-forming position on said other end of the body, which consists in providing the container with a sealing strip on its inside and in overlying relation to portions of the closure flaps and tubular body on opposite sides of the fold lines on which said flaps are foldable into closure-forming position, folding said flaps and the overlying portions of said sealing strip into closure-forming position, holding the outermost of said flaps in said position, and delivering compressed air into the body of said container through said filling opening so as to cause said compressed air to press said flaps into intimate, adhesively secure interengagement, said sealing strip serving to resist passage of compressed air into the zones of interengagement between said flaps.
